Frank Kent

UNITED STATES PATENT OFFICE.

MARTIN L. BEISTLE, OF SHIPPENSBURG, PENNSYLVANIA.

ORNAMENTAL BASKET STRUCTURE.

Application filed February 5, 1926. Serial No. 33,256.

This invention relates to ornamental articles including a flat section formed of folded tissue paper and adapted for conversion into a relatively large decorative structure when the folded sections are opened or expanded.

The invention relates particularly to an ornamental basket and has for its object the provision of a single continuous member 10 forming the handle and base for the basket portion. A vertical slot is formed in the lower part of the base into which is fitted the folded tissue member which is adapted to form when expanded the circular bowl 15 of the basket. By thus using a continuous base member on which the foldable parts are mounted a very rigid and sturdy device is produced.

While I have disclosed a single embodiment of the invention for purposes of illustration, it should be understood that the structure may be modified in various ways without departure from the true spirit and scope of the invention as hereinafter defined 25 and claimed.

In the drawings:—

Fig. 1 is a perspective view of a basket in expanded condition.

Fig. 2 is an elevation of the basket in 30 folded condition.

Fig. 3 is an elevation of the base member.

Fig. 4 is a section on line 4—4 of Fig. 2.

Referring more particularly to the drawings, at 10 is shown the flat base member 35 formed of a continuous piece of cardboard or other suitable material, having a handle portion 11 and a bottom portion 12. A vertical slot 13 extends upwardly from the lower edge of the base member. The flat 40 semi-circular member 14 is formed of tissue so pasted together that it has a cellular structure when expanded. The member 14 is inserted at its center in the slot 13, and is fastened at 13^a to opposite sides of the base 45 member, as will be clear from Figs. 2 and 4.

An arc-shaped end piece 15 is secured to the part of expandable member 14 exposed on each side of the base member. This end piece protects the fragile expandable member 50 from injury when the basket is folded, and provides a means for holding the member 14 in a fully expanded condition. The end piece 15 visible in Fig. 2 is formed with a tongue 16 which, in unfolding member 14,

is carried over toward the right and secured 55 in the notch 17. A similar holding means is provided for the opposite end piece 15.

When both end pieces are secured in open position the member 14 is fully expanded and provides a circular bowl-shaped basket 60 as shown in Fig. 1.

A folded member 18 may be attached to the base member if desired. This member 18 when unfolded produces the eggs 19 in the manner disclosed in my copending application No. 35,868, filed June 9, 1925.

By forming the base member with a slot 13 closed at one end, it is unnecessary to use a wire stitch or any other separate means to secure together the laminations of the 70 expandable member 14 as required in the structure of my copending application.

It will be apparent that the base member may be of any desired shape or design, and that the expandable basket portion may be 75 given various forms without departing from the spirit of the invention.

What I claim is:—

1. In an ornamental article, a base member having a slot therethrough, and an expandable member of cellular tissue inserted 80 in said slot.

2. In an ornamental article, a base member having a slot therethrough, and a flat expandable member of cellular tissue inserted 85 in said slot and adapted when expanded to simulate a body extending beyond both sides of said base member.

3. In an ornamental article, a base member having formed therein a slot closed at 90 one end, and an expandable member inserted in said slot.

4. In an ornamental article, a base member having formed therein a slot closed at 95 one end, and an expandable member inserted in said slot and fastened to opposite sides of said base member.

5. In an ornamental article, a base member having formed therein a slot, an expandable member inserted in said slot and fastened to opposite sides of said base member, and end pieces secured to the exposed sides 100 of said expandable member.

6. In an ornamental article, a base member having formed therein a slot, an expandable member inserted in said slot and fastened to opposite sides of said base member, and end pieces secured to the exposed 105 sides of said expandable member.

sides of said expansible member, said end pieces carrying fastening means adapted to engage with the base member.

7. In an ornamental basket, a base mem-

ber having a handle portion, said base mem-
ber having formed therein a slot, and an
expansible member inserted in said slot.

8. In an ornamental basket, a base mem-
ber having a handle portion, said base mem-
ber having formed therein a slot, and an
expansible member inserted in said slot and
fastened to opposite sides of said base
member.

9. In an ornamental basket, a base mem-
ber having a handle portion, said base mem-
ber having formed therein a slot, an ex-

pansible member inserted in said slot and
fastened to opposite sides of said base mem-
ber, and end pieces secured to the exposed
sides of said expansible member.

20

10. In an ornamental basket, a base mem-
ber having a handle portion, said base mem-
ber having formed therein a slot, an ex-
pansible member inserted in said slot and
fastened to opposite sides of said base mem-
ber, and end pieces secured to the exposed
sides of said expansible member, said end
pieces carrying fastening means adapted to
engage with the base member.

25

In testimony whereof I affix my signature.

MARTIN L. BEISTLE.
